ROTARY CORE BIT

Leonard S. Copelin, Los Angeles, Calif.

Application March 4, 1935, Serial No. 9,158

7 Claims. (Cl. 255—72)

This invention relates generally to rotary drills, such as are employed for earth-boring operations. More particularly it relates to the construction of cutting heads or bits for drills of the core-forming type.

It is an object of the invention to provide a drill bit which will afford efficient and reliable operation and which will not tend to bind itself within the hole being drilled.

10 It is a further object of the invention to provide a bit characterized by utmost simplicity of construction and by the absence of conventional pilot teeth surrounding the core passage.

Further objects of the invention will appear from the following description in which the preferred embodiment of the invention has been set forth in detail in conjunction with the accompanying drawings.

20 Referring to the drawings:

Fig. 1 is a side elevational view, in cross-section, showing a rotary core drill incorporating the present invention.

Fig. 2 is a side elevational view, showing the cutting head or bit incorporated in the drill of 25 Fig. 1.

Fig. 3 is a view similar to Fig. 2, but with the bit rotated through 90°.

Fig. 4 is a cross-sectional detail taken along the line 4—4 of Fig. 1.

30 Fig. 5 is a cross-sectional detail taken along the line 5—5 of Fig. 1.

Fig. 6 is a bottom plan view of the drill shown in Fig. 1.

The drill as illustrated in Fig. 1 consists generally of a drill body 10, having a cutting head or drill bit 11 secured to the lower end of the same, as by means of a threaded connection 12. The outer core barrel 13 is secured to the upper end of the drill body. Within the outer barrel 13 40 there is an inner core barrel or retainer 14, the lower end of which is secured to the drill body 10. The cutting head is provided with a vertical opening 16 concentric with the axis of rotation, which permits a core to progress upwardly into the core 45 retainer 14.

The head or bit 11 consists of a body 17, carrying a plurality of circumferentially spaced wing teeth 18a and 18b. A desirable contour for the body 17 is illustrated in Figs. 1, 2 and 3. Thus, in 50 this instance the body is generally tapered downwardly over beveled annular surface areas 18 and 19 which are made to conform substantially to truncated cones concentric with the axis of rotation. The junction between the two truncated cones, indicated at 21, represents the region of

demarcation between the different angles to which the surfaces 18 and 19 are beveled. At the lower end of the bit body there is a lip 22 surrounding the core opening 16, and this lip is substantially uninterrupted except for portions of 5 the wing teeth, instead of being provided with pilot teeth as in conventional constructions.

It is desirable from the standpoint of simplicity to form the wing teeth integral with the body of the bit, although suitable detachable mountings can be provided if desired. The wing teeth 18a may be duplicates, and are carried on opposite sides of the bit. Each of these teeth affords an advancing face 23 in a general plane inclined with respect to the vertical. Below the region of 15 the surface area 19 and the lip 22, each wing tooth 18a provides a depending tooth portion 24. Thus each of the wing teeth 18a is formed to afford lower substantially horizontal cutting edges 26 and 27, which are stepped to cut on areas 20 of different diameters. In Fig. 1 these areas have been designated by numerals 28 and 29. The inner edges of tooth portions 24 extend slightly inwardly of the periphery of opening 16, in order to form a core 32 of proper diameter to pass 25 upwardly into the core retainer. The advancing face of each tooth portion 24 is shown as being a continuation of the general advancing face 23 for the corresponding wing tooth.

The wing teeth 18b differ in positioning and 30 proportioning in order to afford a desired reaming action. Each of these teeth has an advancing face 33, which lies generally in a vertical plane. Lower depending tooth portions 34 are provided, corresponding to the tooth portions 24 for wing 35 teeth 18a. Lower stepped cutting edges 36 and 37 are provided, which likewise act on areas of the formation at different diameters. Outer vertical reaming edges 38 are provided, which extend to radii beyond the corresponding outer 40 edges 39 for the teeth 18a.

With respect to the positioning of the lower cutting edges 26 and 36, all of these edges preferably lie in a common plane normal to the axis of rotation. However, the lower edges 37 lie generally in a plane normal to the axis of rotation, which is at a slightly higher elevation than a corresponding plane coincident with the cutting edges 27 for wing teeth 18a. In general, the advancing faces of all the wing teeth are preferably 45 at an angle, with respect to radii coincident to the same and normal to the axes of rotation. In other words, the advancing faces are disposed non-radially, so as to tend to urge cuttings outwardly as the bit rotates.

In combination with the features described above, provision is made for delivering lubricating mud to the bit, in such a manner as to insure proper carrying away of cuttings without clogging. Thus the body of the bit is provided with substantially vertical passages 41 for lubricating mud, there being one passage for each of the main teeth. It is desirable to have these passages flattened in cross-section, as illustrated in Fig. 6, in order to avoid undue erosion of metal by the scouring action of sand. In this connection it may be explained that with a circular passage for the delivery of lubricating mud, the stream of mud, together with sand, tends to swirl rapidly, with the result that there is a severe scouring action with a rapid wear away of the metal. With a flattened passage, however, the formation of such swirling currents is inhibited, with the result that wear is minimized and the useful life 20 of the bit materially increased.

The lower discharge ends 42 of the ports 41 are located directly in front of the advancing faces 23 and 33 of the wing teeth, in areas intermediate the outer and lower areas of these advancing faces, as is evidenced in Fig. 1. Likewise, the discharge is immediately above the junction 21 between the surface areas 18 and 19. With respect to the formation being acted upon, the discharge ends of the ports 41 are likewise substantially directly above the shoulder 43 formed at the junction between the areas 28 and 29. As will be presently explained, such an arrangement for the ports 41 is conducive to efficient action of the rotary mud in carrying away cuttings and preventing clogging.

As representative of a suitable expedient for delivering rotary mud to the ports 41, the upper end of the bit body is shown provided with an annular recess 44, which communicates with all of the ports 41 and which in turn communicates with a greater number of ports 46 formed in the drill body 10. According to conventional practice, lubricating mud is circulated downwardly through the space 41 between the inner and outer core barrels, to be delivered through passages 46, and from thence through the ports 41.

It is generally desirable to incorporate suitable core catching means in conjunction with the drill bit. Such a core catcher has been indicated generally at 48.

Operation of the invention described above can now be explained as follows:—During a drilling operation, the lower tooth portions 24 and 34 cut on the area 28 of the formation, and therefore define the core 32 in addition to performing a substantial part of the drilling operation. Cutting edges 27 of the teeth 18a (which have the inclined advancing faces 23) cut upon the larger diameter area 29. Wing teeth 18b, and particularly the vertical edges 38, perform a reaming operation upon the side walls of the hole, and, because of the vertical positioning of the same as distinguished from the inclination of the corresponding edges 39 of teeth 18a, the hole is formed with smooth side surfaces, without a so-called cork-screw effect such as is common in bits of the prior art. Because of the absence of the usual pilot teeth on the lip 22, more bearing pressure is made possible upon the lower cutting edges, with the result that an increase in the rate of drilling is made possible. Likewise elimination of pilot teeth greatly reduces frictional heat on the core, and therefore the core does not tend to dry with consequent sticking to the throat or plugging of the bit. As indicated in a general

way by the arrows in Fig. 1, lubricating mud discharged from the ports 41 is distributed over the advancing faces of the wing teeth, with an effective flow of a substantial part of the mud down into the regions in advance of the lower tooth portions 24 and 34. Thus, cuttings are effectively carried away from all of the active cutting and reaming edges, to facilitate a rapid cutting rate and to prevent clogging or balling up of material about the teeth.

Due to the efficient and effective manner in which lubricating mud is circulated to the bit, and due also to the efficient reaming action afforded by the vertical edges 38, the drill is not subject to jamming in the hole and can always be raised without difficulty.

It is to be understood that the various cutting and reaming edges can be reinforced by suitable hard metal alloy, in order to afford greater resistance to wear. Such practice, however, is common in the manufacture and repair of rotary bits, and need not be described in detail.

I claim:

1. In a rotary earth-boring drill, a cutting head comprising a body provided with at least four circumferentially spaced teeth, two of the teeth on opposite sides of the head having advancing faces inclined with respect to the vertical and having stepped lower cutting edges, the other teeth being interposed with respect to the first-named teeth and having substantially vertical advancing faces, said last-named teeth likewise having stepped lower cutting edges and extending to a diameter beyond the outer diameter of the first-named teeth.

2. In a rotary earth-boring drill, a cutting head comprising a body provided with at least four circumferentially spaced teeth, two of the teeth being disposed on opposite sides of the head and having advancing faces inclined with respect to the vertical, said teeth likewise having stepped lower cutting edges, the other teeth being interposed with respect to the first-named teeth and having substantially vertical advancing faces, said last-named teeth likewise having stepped lower cutting edges and extending to a diameter beyond the outer diameter of the first-named teeth, the lowermost cutting edges of all the teeth being substantially coincident with a common plane normal to the axis of rotation of the drill.

3. In a rotary earth-boring drill, a cutting head comprising a body provided with at least four circumferentially spaced teeth, two of the teeth being disposed on opposite sides of the head and having advancing faces inclined with respect to the vertical, said teeth also having at least two stepped lower cutting edges, the other teeth being interposed with respect to the first-named teeth and having substantially vertical advancing faces, said last-named teeth likewise having at least two stepped lower cutting edges and extending to a diameter beyond the outer diameter of the first-named teeth, the lowermost cutting edges of all the teeth being substantially coincident with respect to a common plane normal to the axis of rotation of the drill, the uppermost lower cutting edges of the first-named teeth being at a lower elevation than the uppermost lower cutting edges of the second-named teeth.

4. In a rotary earth-boring drill, a cutting head comprising a body provided with at least four circumferentially spaced teeth, two of the teeth on opposite sides of the head having advancing faces inclined with respect to the vertical and

- having stepped lower cutting edges, the other teeth being interposed with respect to the first-named teeth and having substantially vertical advancing faces, said last-named teeth likewise 5 having stepped lower cutting edges and extending to a diameter beyond the outer diameter of the first-named teeth, the body being provided with ports for the delivery of lubricating mud directly to the advancing faces of all of the 10 teeth, there being a port for each of the teeth, with each port discharging downwardly into a region intermediate the edges of the associated advancing face.
5. In a rotary earth-boring drill, a cutting head 15 comprising a body provided with at least four circumferentially spaced wing teeth, two of the wing teeth being disposed on opposite sides of the head and having advancing faces inclined with respect to the vertical, said teeth also having at least two lower cutting edges stepped to cut on 20 areas at different diameters, the other wing teeth being interposed with respect to the first-named teeth and having substantially vertical advancing faces, said last-named teeth likewise having at least two lower cutting edges stepped to cut on 25 areas at different diameters and also having outer substantially vertical reaming edges extending to a diameter beyond the outer diameter of the first-named teeth, the body being provided 30 with downwardly-extending ports for delivering lubricating mud to the advancing faces of the teeth, there being a port for each tooth, with the discharge end of each port intermediate the edges of the associated advancing face, the discharge 35 end of each port being substantially directly above the junction of the two areas to which the lower edges of the first-named teeth are adapted to cut.
6. In a rotary earth-boring drill, a cutting head
- comprising a body provided with at least four circumferentially spaced wing teeth, two of the wing teeth on opposite sides of the head having advancing faces inclined with respect to the vertical and having stepped lower cutting edges, 5 the other wing teeth being interposed with respect to the first-named teeth and having substantially vertical advancing faces, said last-named teeth likewise having stepped lower cutting edges and also having substantially vertical 10 reaming edges extending to a diameter beyond the outer diameter of the first-named teeth, the body having an opening therethrough for passage of a core, the outer contour of the body being tapered downwardly to form a substantially unobstructed annular lip surrounding the lower end of said opening, the lowermost cutting edges of the first-named teeth extending below said lip to form a core for passage through said opening. 15
7. In a rotary earth-boring drill, a cutting head comprising a body provided with at least four circumferentially spaced teeth, two of the teeth being disposed on opposite sides of the head and having at least two stepped lower cutting edges, 20 the other teeth being interposed with respect to the first-named teeth, and having at least two stepped lower cutting edges, said last-mentioned teeth extending to a diameter beyond the outer diameter of the first-named teeth, the lowermost cutting edges of all the teeth being substantially coincident with respect to a common plane normal to the axis of rotation of the drill, the uppermost lower cutting edges of the first-named teeth being at a lower elevation than the uppermost lower cutting edges of the second-named teeth. 25
